HENRY J. STUART, OF DERBY, CONNECTICUT, ASSIGNOR TO ROBERT N. BASSETT COMPANY, INCORPORATED, OF SHELTON, CONNECTICUT, A CORPORATION OF CONNECTICUT.

HOSE-SUPPORTER CLASP.

1,283,953.

Specification of Letters Patent.

Patented Nov. 5, 1918.

Application filed March 29, 1916. Serial No. 87,649.

To all whom it may concern:

Be it known that I, HENRY J. STUART, a citizen of the United States, residing at Derby, in the county of New Haven and State of Connecticut, have invented a certain new and useful Improvement in Hose-Supporter Clasps, of which the following is a specification.

My invention relates to button clasps for hose supporters and like articles, but more particularly to that class of the same wherein fabric or other soft material is disposed over the front face of the base of the button, and its principal object is to provide a device of this character to which the fabric material may be secured during the process of assembling the button without resorting to the expedient of sewing or stitching.

In the drawings:

Figure 1 is a front view of the clasp;

Fig. 2, a central longitudinal section but showing the loop swung forwardly out of engagement with the button;

Fig. 3, front and longitudinal sectional views of the button-carrying tape;

Figs. 4 and 5, sectional views showing different positions of the tape in relation to the button during the process of assembling;

Fig. 6, a detail view of the button; and

Figs. 7 and 8, detail views of modifications.

The button clasp consists of an attaching loop A, a button loop B and a button tab or tape C which carries a button D at its lower extremity. The button loop B, which is connected to the lower side of the attaching loop A by a lip E projecting from the upper side thereof, is provided with a bridge F and has the sides of its lower extremity contracted to engage the shank of the button D. With the exception of the button D and the manner of attaching the same to the tab C the device thus far described is one of the common forms of button clasps well known in the art. The button D consists of a circular, or substantially circular, metal base 2. Projecting outwardly and riveted to the base 2 is a wire stud 3. The stud 3 is headed to form a convex head 4, which is preferably provided with a downwardly projecting peripheral biting edge 5. The elastic rubber cap or collet 6 is shaped to form a head 7 and a shank 8. The collet 6 is provided with a central aperture 9 having an

inside cylindrical wall 10 flared outwardly 55 at its upper extremity. The diameter of the wall 10 is less than that of the head 4 and preferably less than that of the shank of the stud 3. The button tape or tab C has one of its extremities *a* punched to form 60 adjacent apertures 11, 12 and its other extremity *b* also punched to form an aperture 13. One way of assembling the button is to first rivet the stud 3 to the base 2. Then the extremity *b* of the tape is folded 65 on itself and slipped over the head 4 of the stud, or to be more exact the head 4 is slipped through the aperture 13 of the tab so that its upper edge 14, if desired, will project beyond the periphery, or the upper 70 end of the base 2. The tab is then carried around in back of the base 2 and its extremity *a* folded, preferably on a crease, midway between the apertures 11, 12 so that the latter will register when the two layers 75 of the fold are brought together as shown in Fig. 5. The apertured extremity *a* is then slipped over the head 4 of the stud, the latter passing through the registering apertures 11, 12 as shown in Fig. 5. The elastic rubber collet is then sprung over the stud, which passes through the aperture 9 therein, filling the space between the under side of the head of the stud and the front face of the fabric covered base, and securely holds 85 the folded extremities of the tab against the base as shown in Fig. 2. This causes the biting edge 5 to become embedded in the flaring extremity of the wall 10 of the aperture 9 of the collet. In this manner the 90 button is assembled and the collet is permanently secured to the stud and co-acts with the base 2 to prevent the folded extremities of the tab from displacement or slipping out of alignment. Should the tab 95 depend from the upper portion of the clasp in the manner shown the extremity *a* is passed forwardly through the attaching loop A and rearwardly over the bridge F before the extremity *a* is slipped over the stud. 100 When the tab is wider than the base of the stud as shown the base is covered and concealed, thereby obviating any disadvantages incident to the exposure of a metal part. In the above description the collet has been 105 referred to as being made of elastic rubber, yet a collet made out of any other springy or yielding material may be employed pro-

vided it can be slipped over the head of the stud and hold the fabric securely to the base. It should be observed that the end edges of the tab are embraced between the 5 layers of and concealed inside the folds, thereby preventing the same from raveling and also from presenting rough edges on the exterior surface of the tab, and it should further be observed that no stitching or 10 sewing whatever is required in assembling the parts since the stud and collet may be the sole means for fastening the fabric to the button.

The secured extremity of the tab may be 15 fastened in other ways than that above described, a particular instance being shown in Fig. 7 in which the extremity *c* of the tab *G* is folded so as to form three layers, 16, 17 and 18 provided with registering aper- 20 tures through which the stud 19 is passed and the collet sprung over the same in the same manner as above described. It should be noticed that in this modification only the front side of the base plate is covered and 25 that the head 20 is not provided with downwardly projecting biting edge as shown in Fig. 2.

In the modification shown in Fig. 8 the extremity *d* of the tab *H* is folded so as to 30 form two layers 21, 22 of fabric material provided with registering apertures over the front of the base plate 23 and a single layer 24 over the back of the base plate. In this construction the base plate 23 is provided 35 with two small studs 25, 25 over which the registering apertures are passed in the same manner as over the single stud in the preceding constructions and the collet or cap 26, which is provided with suitable recesses 40 extending only partially through the same for the reception of these studs, is made substantially solid. This collet is of a form well known in the art and is provided with flanges 27, 27 along the sides of its head 45 portion and the base plate is made substantially rectangular. It should be observed that in folding the fabric in the manner last mentioned no folds appear when the same is viewed from the front so that the 50 front side of the tab may present a flush surface throughout its entire length.

It should be further observed that in securing the fabric to the button the plurality of layers forming the folds in the fabric 55 present a cushion-like or yielding surface against which the garment is pressed by the button loop when the latter engages the button.

Attention is called to the fact that the tape 60 may be supported in other ways besides folding it around one of the button clasp members as above described and further the button tab or supporting tape may be attached to any other part of the hose sup- 65 porter according to convenience. It should

be further noticed that it is not necessary that the folded fabric material referred to herein as the button tab should be the sole means for carrying the button, or carry the button at all, since my invention comprehends fabric, or other suitable soft material, even should the same not be employed as a button-carrying tape.

Having now described my invention what I claim and desire to protect by Letters Pat- 75 ent is:

1. In a button clasp a base plate provided with a projecting stud, a tape folded on itself and provided with registering apertures through which the stud extends, and a recessed elastic member surrounding the stud in front of the folded tape to fasten the latter to said base plate.

2. In a button clasp a base plate having its front face covered with tape which is 85 folded so that one of its extremities is embraced between said plate and one of the layers of said tape, a member mounted on said base in front of said tape and means for causing said member to co-act with said 90 plate to fasten said extremity to said base.

3. In a button clasp a button comprising a circular base plate carrying a projecting shank and head and a button-carrying tape folded around the base plate to conceal the 95 latter between the layers of the tape, the said tape having one of its extremities folded on top of the base plate and provided with registering apertures the edges of which are confined between the front face of the base 100 plate and the under side of the shank of the button.

4. A button clasp comprising a button base provided with a stud, a tape having one of its extremities apertured and folded 105 around said base plate so that the stud extends through the aperture and having its other extremity folded and provided with registering apertures through which the stud also extends, and a collet made of 110 spring like material surrounding said stud in front of said extremities of the tape to secure the latter to the button.

5. In a button clasp a base plate carrying a headed stud, a tape having one of its extremities folded on itself and provided with registering apertures through which said stud extends, the end of said extremity being disposed in back of the front layer of said fold, and a recessed cap made of spring-like 120 material surrounding the stud in front of the tape fabric to fasten the latter to said base plate.

6. A button clasp comprising a folded fabric tape provided with registering apertures, a support over which said tape is folded, a button base provided with a projecting headed stud, and an apertured collet made of spring-like material, the apertured 125 layers of said fabric surrounding the stud 130

and the said collet also surrounding the stud on top of the fabric to secure the latter to the button.

7. In a button clasp a support, a base plate provided with a projecting stud, a tape folded over said support and having apertured extremities through which said stud extends, and a recessed elastic member surrounding the stud in front of said extremities to fasten the latter to the base plate.

8. In a button clasp a base plate having

its front face covered with tape, a support over which said tape is folded, the said tape having its extremities embraced between said plate and one of the layers of the tape, and means mounted on said plate in front of said tape which co-act with said plate to fasten said extremities. 15

In testimony whereof I have hereunto set my hand this 15th day of March, 1916.

HENRY J. STUART.
